UNITED STATES PATENT OFFICE.

DAVID I. ECKERSON, OF WORCESTER, NEW YORK, ASSIGNOR OF ONE-HALF
TO JULIUS T. HADSELL AND PORTER R. HADSELL, OF SAME PLACE.

DESIGN FOR A TUB.

SPECIFICATION forming part of Design No. 30,136, dated February 7, 1899.

Application filed November 29, 1898. Serial No. 697,800. Term of patent 14 years.

To all whom it may concern:

Be it known that I, DAVID I. ECKERSON, a citizen of the United States, residing at Worcester, in the county of Otsego and State 5 of New York, have invented and produced a new and useful Design for Tubs, of which the following is a specification, reference being had to the accompanying drawings, forming part thereof.

10 The figure is a perspective view of a tub embodying the design.

Like reference characters designate corresponding parts in the different views.

The body of the tub consists of the side 15 pieces 3, the end pieces 4, and the bottom 5. These several parts are so connected and joined as to form a receptacle with an opening substantially rectangular in shape. The bottom 5 is shaped so that its ends 6 are in 20 the form of semicylinders connected by the curved portion 7. By forming the bottom in

this way the body is practically divided into two compartments by the upper edges of the end portions and the curved portions connecting them.

To the sides of the tub are attached the legs 9 by the bolts 10 and the screws 11. The legs at each end of the tub are connected by the cross-piece 12.

A cover 13 is placed over the mouth of the 30 tub.

Having thus described my invention, what I claim as new, and desire to secure by Letters Patent, is—

The design for a tub, as herein shown and 35 described.

In testimony whereof I hereunto affix my signature in the presence of two witnesses.

DAVID I. ECKERSON.
